MEANS FOR REPAIRING AND SECURING
SCREENS

Ralph W. Friday, Pittsburgh, Pa.

Application June 26, 1931. Serial No. 547,076

7 Claims. (Cl. 156—14)

This invention relates to a means, for repairing wire screens, or for securing two wire screens to each other, or for securing the edge of a sheet of wire screen to prevent fraying or opening of 5 the screen mesh at the ends.

The object of this invention in its broadest aspect is to secure two pieces of screen cloth to each other.

Another object of the invention is to provide 10 a means of securing the ends of a sheet of wire screen against fraying and consequent weakening.

Another object of the invention is to provide 15 screen patches already treated with a securing element in position around the rim of the patch to constitute a border by means of which the patch may be readily attached and secured to a screen to cover a hole therein.

In order to secure one piece of screen to another piece of screen, or in order to prevent the 20 ends of the wire screen from fraying or separating, I work or imbed the wire screen into a narrow strip or wire of soft pure lead. Where one piece of screen is to be secured to another 25 piece of screen, both pieces are imbedded in the wire or strip of lead on opposite sides thereof in such manner that the lead is intimately interlocked or bonded with the wire mesh of the screen so that the screen cannot be readily separated from the lead strip.

In one form of the invention, a small piece of 30 screen cloth, which is to be used as a patch, is provided with a narrow border of soft pure lead wire which has been worked into the screen mesh 35 so that it is securely interlocked therewith. The patch is then ready to be secured to another sheet of wire screen, for the purpose of covering a hole therein, for example, by tightly pressing or by lightly beating the lead border into the mesh of 40 the screen that is to be repaired.

The same principle of securing two pieces of 45 sheet screen is applicable where it is desired merely to attach the end of one sheet of wire screen to another sheet of wire screen, as where one sheet may not be sufficient in length and it is necessary to secure another piece thereto, to render it suitable for the purpose for which the screen is to be used.

50 Another aspect of the invention involves the use of the soft lead wire as a means for securely anchoring the edge of a sheet of screen in the usual soft wooden frame with which the sheet of wire screen is to be assembled.

55 The various modifications referred to are

illustrated and described in the accompanying drawing, in which

Figure 1 is a front elevational view of a usual screen to which a patch has been applied in accordance with the principles of this invention; 60

Figure 2 is a front elevational view of a screen patch in the form in which it is shown applied to the screen in Figure 1;

Figure 3 is an edge view of the screen patch of Figure 2 showing the disposition of a strip or 65 wire of soft pure lead when first placed against the screen;

Figure 4 is a view of the screen in Figure 3 after the wire or strip of soft pure lead has been 70 pressed into intimate interlocking relationship with the screen;

Figure 5 is a similar view showing a magnified section in which the wire or strip of soft lead is used to secure two pieces of screen together;

Figure 6 is a front elevational view showing the 75 manner in which two edges of screen are secured together to provide a longer sheet of screen;

Figure 7 is a front elevational view illustrating an arrangement whereby one edge of a sheet of screen is anchored in a wooden frame, with which 80 the sheet of screen is to be assembled as a window screen or as a door screen; and

Figure 8 is a side sectional view of the assembly shown in Figure 7 illustrating the manner in which the soft lead strip, which holds the ends 85 of the screen wires against fraying, serves also as an anchoring element which is embedded in the wooden frame.

As is illustrated in Figure 1, a large screen 10, having a hole 11 therein, is repaired by means of 90 a patch 12 being placed over the hole 11 and secured to the screen 10 to be held in position against displacement.

The patch 12, as is illustrated in Figure 2, comprises a small piece of wire screen 13, the outer 95 edges of which are bordered by a soft narrow strip or wire of soft pure lead 14 which is pressed into the wire screen 13 to establish a bond of close intimate interlocking relationship with the wire screen, so that the lead border is substantially integral with the screen and closely adherent thereto.

Because of the soft ductile character of pure lead it may be readily pressed or hammered into a sheet of wire screen in such manner as to form 105 small lugs 15 that enter into the spaces between the wires forming the wire screen. When the screen is well supported on one side, while the lead wire or strip is pressed into, or hammered into, the screen from the other side, the small lug 110

portions 15 entering into the spaces between the wires of the screen will be caused to embrace those wires, thereby forming a closely and intimately interlocked bond between the lead strip 5 and the wire screen, so that the two become substantially integral and closely adherent, as illustrated in Figure 4.

When the screen patch 12 is to be attached to another sheet of screen, the patch 12 is applied 10 to the screen so that the unworked portion of the border of lead strip 14 will engage the surface of the screen to which the patch is to be attached. When the lead border is hammered into position so that it will similarly engage and intimately interlock with the screen that is to be repaired, or 15 to which the patch is to be attached, the lead strip will similarly engage that screen and form a tightly interlocked bond which functions substantially as a soft metal weld between the two 20 sheets of metal screen. A closely adherent and tightly secured bond is thus established between the two sheets of screen.

This same method of bonding two pieces of screen 16 and 17 may be employed, as illustrated in 25 Figure 6, to secure the edges of two sections of screen cloth together.

Such a bond, as illustrated in Figure 6, or in Figure 2 in connection with the patch, also serves to prevent fraying or dispersing of the ends of the 30 screen cloth, and thereby strengthens the cloth since it prevents the weakening at the edges with consequent stretching and weakening in the center of the screen.

In order to further utilize the lead wire bonding 35 medium as an anchoring element for the screen, the lead strip 14, after being bonded to the ends of a wire screen cloth along its edge, may be hammered into, and imbedded in, the wooden frame 18 of a window screen or door 19 with which the 40 sheet of wire screen is to be assembled, as illustrated in Figures 7 and 8.

My invention is not limited to the particular 45 application of the screen patches illustrated and

described herein, nor to any particular bonding metal, but may be variously modified without departing from the spirit and scope of the invention as set forth in the appended claims.

I claim as my invention:

1. An article of manufacture consisting of a strip of screen having a border of soft workable metal secured thereto. 80
2. An article of manufacture consisting of a strip of screen having a border of lead strip 85 worked into intimate interlocking relationship with the screen.
3. An article of manufacture consisting of a strip of screen having a border of soft lead strip 90 worked into intimate interlocking relationship with the screen along at least one edge thereof.
4. An article of manufacture consisting of a strip of screen having a strip of soft workable metal secured thereto along one edge to hold the 95 strands of the screen against fraying.
5. An article of manufacture consisting of a strip of screen having a binding material along an edge thereof, which material may be readily worked into intimate interlocking relationship with a similar strip of screen to which the article 100 is to be attached.
6. An article of manufacture consisting of a strip of screen having a binding element at an edge thereof, part of said element being securely worked into intimate interlocking relationship 105 with the screen, and part of the element being available to be worked into intimate interlocking relationship with a similar strip of screen to which the article is to be attached.
7. An article of manufacture consisting of a screen patch having a binder material secured at predetermined locations along one surface of the patch whereby the patch may be applied to cover a hole in another screen and secured in position to 110 such other screen with the patch and the screen 115 in flat parallel plane relationship.
